United States Patent Office

Des. 194,684

Patented Feb. 26, 1963

194,684

COMBINED BENCH, VANITY DESK AND CHEST UNIT

Merton L. Gershun, Miami Beach, Fla., assignor to American Furniture Co., Inc., Martinsville, Va., a corporation of Virginia

Filed May 24, 1961, Ser. No. 65,328

Term of patent 7 years

(Cl. D33—7)

Fig. 1.

Fig. 2.

Fig. 3.

Fig. 4.

FIGURE 1 is a perspective view of a combined bench, vanity desk and chest unit embodying my new design;

I claim:

The ornamental design for a combined bench, vanity desk and chest unit, substantially as shown and described.
